Term of patent 14 years

(Cl. D2—3)

To all whom it may concern:

Be it known that we, David A. McCowan, Jr., Barbara A. McCowan, and Peter M. McCowan, subjects of the King of Great Britain, residing in Toronto, county of York, Province of Ontario, Canada, have invented a new, original and ornamental Design for a Beverage Dispensing Apparatus, of which the following is a specification, reference being had to the accompanying drawing forming part thereof.

In the drawing:

Fig. 1 is a top plan view of a beverage dispensing apparatus, showing our new design.

Fig. 2 a front view; and

Fig. 3 a rear view of the dispensing apparatus.

The sides of the apparatus, not shown, are substantially plain except for the continued beading on the top and bottom borders of the lower portion and the top border of the upper portion.

We claim:

The ornamental Design for a beverage dispensing apparatus, as shown and described.

DAVID A. McCOWAN, JR.
BARBARA A. McCOWAN.
PETER M. McCOWAN.
